UNITED STATES PATENT OFFICE

165,896

EXPANSIBLE CHAIN FOR A BRACELET OR SIMILAR ARTICLE

Karl C. Augenstein, Cranston, R. I., assignor to
Speidel Corporation, Providence, R. I., a cor-
poration of Rhode Island

Application June 29, 1951, Serial No. 15,718

Term of patent 14 years

(Cl. D45—4)

To all whom it may concern:

Be it known that I, Karl C. Augenstein, a citizen
of the United States of America, residing at
Cranston, county of Providence, and State of
Rhode Island, have invented a new, original, and
ornamental Design for an Expansible Chain for a
Bracelet or Similar Article, of which the follow-
ing is a specification, reference being had to the
accompanying drawing, forming a part thereof.

Fig. 1 is a top plan view of an expansible chain
embodiment my new design with the links in con-
tracted position;

Fig. 2 is a view similar to Fig. 1 with the links
in an expanded position, portions of the con-
ventional appearing bottom links being visible
between the expanded top links;

Fig. 3 is an enlarged top plan view of a single
top link of the expansible chain; and

Fig. 4 is an edge elevational view looking from
right to left at the link shown in Fig. 3.

I claim:

The ornamental design for an expansible chain
for a bracelet or similar article, substantially as
shown and described.

KARL C. AUGENSTEIN.
